UNITED STATES PATENT OFFICE.

EDWIN B. SINTZENICH, OF ROCHESTER, NEW YORK.

BALANCED VALVE.

SPECIFICATION forming part of Letters Patent No. 700,985, dated May 27, 1902.

Application filed July 28, 1900. Serial No. 25,127. (No model.)

To all whom it may concern:

Be it known that I, EDWIN B. SINTZENICH, a citizen of the United States, and a resident of Rochester, in the county of Monroe and 5 State of New York, have invented certain new and useful Improvements in Balanced Valves, of which the following is a specification.

The invention relates to balanced valves for steam-engines, pumps, air-motors, &c. Its 10 object is to produce a means of balancing a slide-valve by means that are easily attached to it and to provide means for packing the balancing mechanism or to prevent the escape of steam therefrom.

15 The invention consists in the mechanism hereinafter described and claimed.

In the drawings, Figure 1 is a vertical longitudinal section through the ports and steam-passages of a cylinder and through a slide-20 valve having one or more balancing devices attached thereto. Fig. 2 is a top plan view of one-half of a modified form of one of my balancing devices, and Fig. 3 is a vertical cross-section on the diameter of the mechanism shown in Fig. 2.

25 The mechanism herein shown will be described as applied to the slide or D valve of an ordinary steam-engine cylinder, although the device is capable of application to other 30 constructions by means within the skill and knowledge of those acquainted with the art of motors and pumps of various kinds.

In Fig. 1 is a portion of the cylinder of an ordinary steam-engine. a is the exhaust-port 35 thereof. a' a² are the steam-ports. B B are the side walls of a steam-chest. B' is the steam-chest cover. b is the valve-rod. C is the slide-valve, which may be of usual form, or, as shown in the drawings, it may have extended flanges c c on the ends, perforated at 40 c' c', with ports adapted to register at the ends of the stroke of the valve with the steam-ports a' a². The lengthening of the D-valve C, as just described, is for the purpose of giving a 45 firmer base on which the valve rests and to tend to prevent a lifting or tipping of the valve. The side walls B B of the valve-chest are or may be higher than usual in order to accommodate the balancing mechanism now 50 to be described. On the top of the D-valve C is fastened a box E, that is connected with the interior cavity of the valve C by a proper

passage. In the present instance this passage is a small bore e' through a bolt E', that fastens the box E to the valve-seat. If now 55 the pressure within the box E is the same as within the valve C, the valve C would become balanced and there would be no tendency of the valve to rise from its seat, nor would there be any pressure of the valve C 60 downward on its seat except the mere weight of the valve. This will be the case if the box E is made steam-tight and the pressure in the steam-chest is excluded therefrom. The top B' of the valve-chest is used as the station- 65 ary surface just mentioned, and I produce a steam-tight connection as between the box E and the steam-chest cover B' by the following means: The box E is made cylindrical on the outer side of the flange e, and around 70 this cylindrical surface is placed a packing-ring f, that is capable of movement up and down around the flange e. The inside face of the steam-chest cover and the upper edge of the ring f are surfaced to fit closely, and 75 the said ring is lifted by means of a spring f' pressing against the flange e⁰ on the box E or, if desired, pressing upon the top of the valve C, which raises the ring f into contact with the under surface of the valve-chest 80 cover B'. The ring f is split in order to expand and contract and to fit upon the outer surface of the flange e. On the inner surface of the ring is cut a groove f⁰, which ends at points adjacent to where the ring is split, 85 so that the groove f⁰ when the ring f is fitted upon the flange e constitutes a steam-tight cavity. On the lower edge of the ring f is cut another groove f⁰', that, like the groove f⁰, 90 ends adjacent to the point where the ring is split and forms another steam-tight cavity. These two grooves f⁰ and f⁰' are connected by one or more passages f⁰². Beneath the ring f is a base for supporting the packing, consisting in the present instance of a second ring f², 95 that fits against the lower surface thereof and which the spring f' presses against the lower edge of the ring f. On the outside of the ring f is another thin ring f³, that is also split and is so set on the ring f that the split of the last-mentioned ring is covered by the ring f³. 100 Of course the steam is led into the steam-chest and pressure therein is the boiler-pressure. Under this pressure steam passes into

the cylinder through the port c' and the passage a' in the position of the parts shown in Fig. 1 to one end of the cylinder. From the other end of the cylinder steam passes out through the passage a^2 , valve C, and exhaust passage a in this same position of parts. If the area within the packing-ring f is equal to the area of the open ports under the central cavity of the valve C, there would be perfect balancing of the valve and the friction of the valve on its seat would be only that caused by its own weight. Consequently the internal area of the ring f in contact with the valve-chest cover is made less than the area of the open ports at any time under the valve C in order that there should be some excess of pressure tending to keep the valve upon its seat. This pressure is caused by the steam-pressure in the steam-chest and outside of the balancing device and the valve C. Inasmuch as the pressure in the valve-chest is greater than that under the valve C or inside the balancing device, this pressure will tend to lift the ring f^2 against the lower edge of the ring f and by reason of the groove f' and passage f^{02} will cause the ring f^2 to hug the bottom of the ring f very closely. So, also, the pressure upon the split ring f^3 will cause it to fit closely upon the flange e . This operation is arrested in the case of the rings f^2 and f^3 by the grooves f^{00} and f^0 , which act as if they were open ports under (as to the pressure) the ring f^2 and the ring f , whereby there is a greater surface for the action of the outside steam-pressure than there is on the inside of said rings, the same being diminished to the extent of the area of the grooves f^{00} and f^0 . The action of these grooves thus described becomes effective by reason of passages e^0 through the flange e , which connect the interior of the balancing device with both grooves f^{00} and f^0 , being connected with the first through the passage or passages f^{02} . It will be noticed that the inner upper edge of the ring f^0 is recessed or grooved, as at f^{03} , the purpose of this being to cause it to tend to hug the steam-chest cover B' more closely on account of the increased surface for operation of the outside steam-pressure over the surface of the ring f , which takes the pressure against the steam-chest cover. This mechanism is found to be effective and to remain steam-tight, and by reason of the higher pressure in the steam-chest outside of the valve C and the balancing devices over the pressure within the balancing device and inside the valve C the pressure of the valve upon its seat is reduced and said pressure is variable in accord with the pressure of the exhaust inside the valve C, which pressure of the exhaust is increased or reduced inside the balancing device by reason of the communicating passage e' .

In Figs. 2 and 3 there is shown a modified form of the same mechanism in which the ring f is surrounded by another split ring g , outside of which is placed the ring f^3 . The

ring G has a groove g^0 around its lower edge corresponding to the groove f^{00} . One or more passages g^{02} connect the groove g^0 with a groove g^{03} on the upper edge of the ring g , and one or more passages g^{04} connect with a passage or passages f^{04} in the ring f . This passage f^{04} connects with the passage f^{02} mentioned above. Consequently the reduced pressure within the box E permits the outside steam in the valve-chest to cause the rings g and f to hug the box E closely and to press closely against the under side of the steam-chest cover.

In actual practice the spring f' is not found to be enough to cause a perfect and steam-tight fit of the movable rings f and g against the steam-chest cover; but upon employing the grooves and relief-passages leading from them the steam-tight fit of the rings on the box E and upon the steam-chest cover is found to be perfect and to have movement to produce a tight fit and the exclusion of the steam in a way which does not occur without them.

The outside ring f^3 may have, as shown in Fig. 2, a protecting-plate f^{30} , that is fastened in any suitable manner, as by a screw f^{31} , to one end of the ring near where it is split, said plate passing over the split and being held against the opening at the split by the steam-pressure in the steam-chest.

In the top B' of the steam-chest is a hole b' , filled by a movable plug b^{10} . When this plug is removed, the pressure in the interior of the balancing device is always the same as the atmosphere and avoids, among other things, the disturbing effect of back pressure from the cylinder into the D-valve. With this construction the bore e' may be closed by a plug e^{10} , or the bolt E' may be made solid. When the usual form of riding cut-off is employed, the balancing device usually has no fluid-pressure connection with the D-valve, but is merely fastened thereon, and the hole b' is left open.

The box E rests, as shown, on the back of the D-valve C, and so much of the box as rests in contact therewith of course precludes steam-pressure on so much of the valve. I prefer to leave some space between the bottom of the box E and the back of the valve in order that the steam-pressure in the steam-chest, which of course acts in all directions, may get under the box and exert a lifting action which relieves the pressure of the valve C against its seat. The area of surface of the under side of the box E thus exposed to the steam-pressure should be greater than the surface of the open ports under the valve C.

It will be seen that this balancing device may be applied to any of the usual forms of slide-valve without change, except that in some cases the steam-chest has to be increased in height and the under side of the steam-chest cover must be surfaced.

What I claim is—

1. In a balanced valve, a cylinder having in-

let and exhaust ports, a slide-valve for causing inlet and exhaust of steam to the ends of the cylinder, a steam-chest, a box secured to the back of slide-valve and a movable metallic packing supported on a base on said box and fitting the exterior of said box and against the steam-chest cover and having one or more grooves on its surfaces in contact with said box and said base and open passages from said grooves to the interior only of said box, substantially as described.

2. In a balanced valve, a cylinder having inlet and exhaust ports, a slide-valve for causing inlet and exhaust of steam to the ends of the cylinder, a steam-chest, a box secured to the back of the slide-valve, and a movable metallic packing supported in a base on said box and fitting the exterior of said box and against the steam-chest cover and having one or more grooves on its surfaces in contact with said box, said base and said steam-chest cover, and open passages from said groove to the interior only of said box, substantially as described.

3. In a balanced valve, a cylinder having inlet and exhaust ports, a slide-valve for causing inlet and exhaust of steam to the ends of the cylinder, a steam-chest, a box secured to the back of the slide-valve, and a movable metallic packing supported on a base on said box

and fitting steam-tight against the outer surfaces of the box and against the under surface of the steam-chest cover and upon said base, means for pressing said base upward against the steam-chest cover, said packing having grooves on the surfaces pressing against said box and said base, and open connections from said grooves to the interior only of the box, substantially as described.

4. In a balanced valve, a cylinder having inlet and exhaust ports, a slide-valve for causing inlet and exhaust of steam to the ends of the cylinder, a steam-chest, a box secured to the back of the slide-valve, and a movable metallic packing supported on a base on said box and fitting steam-tight against the outer surface of the box and against the under surface of the steam-chest cover and upon said base, means for pressing said base upward against the steam-chest cover, said packing having grooves on the surfaces pressing against the steam-chest cover, said box and said base, and open connections from said grooves to the interior only of the box, substantially as described.
